INFANT GARMENT

This invention relates to a method and means for clothing a male infant.

In infants, diaper rash (an irritation of the skin beneath the diaper) is a common annoyance. Not only is there an irritant effect due to moisture from the infant's perspiration and urine being retained in contact with the skin, but there may also be a burning ammonia dermatitis produced which results from bacterial decomposition of the urine which is held in contact with the skin. The distribution of ammonia dermatitis corresponds to the spread of the urine retained in contact with the skin, which usually encompasses the lower abdominal and groin regions of the infant. The incidence of this irritation and dermatitis is increased by the use of water proof coverings for diapers, which inhibit diaper drying.

A general object of this invention, therefore, is to provide novel means for clothing a male infant which is effective to reduce skin irritation of the type above described.

More specifically, an object of this invention is to provide a garment for clothing a male infant, comprising a covering for the infant's lower abdominal and groin regions having a hole through it which receive the infant's genitalia including the scrotum. With such an organization, urine discharged does not collect in concentrations immediately on his skin. Furthermore, the scrotum of the infant's genitalia functions to maintain the garment properly positioned.

Another object is to provide a novel method of clothing a male infant which comprises enclosing the lower abdominal and groin regions of the infant in a garment, projecting such infant's genitalia including scrotum through a hole in the garment, and then enclosing the first-mentioned garment and genitalia in another garment. Such other garment functions as an absorbing medium for urine discharged.

Another object is to provide a novel garment for clothing a male infant, including a hole extending through it as above-indicated, wherein the garment includes a liquid impervious layer which functions as a barrier preventing urine discharged from traveling through the garment to come in contact with the infant's skin.

A further feature of the invention is the inclusion in the garment of an absorbent layer which, with the garment clothing an infant, is disposed inwardly of the liquid impervious layer. This absorbent layer is effective to absorb perspiration and other moisture which may collect over the skin and promotes comfort.

These and other objects and advantages are attained by the invention, and the same is described hereinbelow in connection with the accompanying drawings, wherein:

FIG. 1 is a back plan view of a garment manufactured in accordance with this invention, having one of its corners opened up to show plies in the garment in partially folded back positions;

FIG. 2 is a cross-sectional view on an enlarged scale of the garment, taken generally along the line 2-2 of FIG. 1; and

FIG. 3 illustrates the garment in operative position enclosing the abdominal and groin regions of an infant, portions of the infant's body being illustrated in dashed outline.

Referring now to the drawings, shown generally at 10 is a garment for use on a male infant constructed according to a preferred embodiment of the invention. The garment takes the form of a rectangular sheet and includes a liquid impervious layer 12, an absorbent ply 14 underlying layer 12, and a support ply 16 underlying the absorbent ply.

Liquid impervious layer 12 may be a rectangular sheet of one of any number of pliable liquid impervious materials, such as, for example, a plastic impregnated cloth. The absorbent ply 14 which is against layer 12 may be a rectangular sheet of absorbent material such as compressed cotton. Support ply 16 may be a rectangular sheet of material such as gauze and is present in the garment to aid in holding the fibers of the absorbent ply in place. Support ply 16 and absorbent ply 14 together form a liquid impervious layer underlying layer 12.

In manufacturing the garment impervious layer 12 may be made with a somewhat greater length than plies 14 and 16.

This enables opposite end margins such as those shown at 12a, 12b to be folded back over the adjacent margins of the absorbent and support plies and then be suitably secured in place as with an adhesive such as shown at 20. In such a manner the various layers in the garment are held together.

Intermediate the ends of the liquid impervious layer, the absorbent ply, and support ply 16 are registered apertures, more specifically oval holes, shown at 28, 30, and 32, respectively. The major axes of the holes extend along the longitudinal axis of the garment. As seen in FIG. 1, the location of the holes is offset from the center and toward one end (the right end in FIG. 1) of the garment.

Referring now to FIG. 3, at 36 are indicated in dashed outline intermediate regions of a male infant's body. Garment 10 shown in solid outline encloses the lower abdominal and groin regions of the infant. Pinning the diaper in place are pins 37. The infant's genitalia, more specifically penis and scrotum, 38, indicated in dashed outline, are shown inserted through registering apertures 28, 30 and 32 in garment 10.

With the garment so positioned the penis lies outside the garment and any urine discharged is prevented from flowing onto the skin by the barrier formed by liquid impervious layer 12. The edges defining apertures 28, 30, 32 rest snugly adjacent the base of the genitalia and because of this snug fit leakage in this region is inhibited. It is very important that the scrotum be inserted through the apertures together with the penis. By so doing a means is provided for maintaining the garment in proper position on the infant with the penis outside the garment. It has been found that with the usual infant, and by reason of the squirming to be expected of such a child, the penis does not tend to remain outside the garment unless positioned with the scrotum as described. Absorbent ply 14, disposed inwardly of the liquid impervious layer is effective to absorb perspiration and other moisture which may collect over the skin and promotes comfort.

Portions of another garment, which may be like a diaper, are indicated at 40. This other or outer garment is placed so as to enclose garment 10 and genitalia 38. The frontal section of garment 40 has been broken away in FIG. 3, better to illustrate the operative position of garment 10. Garment 40 may be of cloth or other liquid absorbent material, and functions to absorb urinary discharge from the infant.

It is a relatively easy matter to cloth the infant with the garments described. Garment 10 is placed in position enclosing the lower abdominal and groin regions of the infant with support ply 16 next to the infant's body, absorbent ply 14 outwardly from the support ply, and liquid impervious layer 12 forming the outside of the garment and outwardly from the absorbent layer. Prior to pinning the corners of the garment in place the genitalia is thrust through apertures 28, 30, 32. Garment 40 may then be pinned in place using procedures similar to those used in clothing an infant with the usual diaper.

While an embodiment of the invention has been described, it should be obvious that variations and modifications are possible without departing from the invention. It is desired to cover all such variations and organizations as would be apparent to those skilled in the art, and that come within the scope of the appended claims.

I claim:

1. A method of caring for a male infant to take care of his urinary discharge comprising covering lower abdominal and groin regions of the infant in a garment, said garment having a hole extending therethrough in a region adjacent the genitalia of such infant, such covering being done with projecting such genitalia including the scrotum through said hole and forming a snug fit about the base of such genitalia with the margins of such hole, placing another garment which is separate from the first-mentioned garment and absorbent against the genitalia including the scrotum and portions of said first-mentioned garment adjacent said hole to form an overlying absorbent cover with the genitalia including scrotum sandwiched between the overlying cover and said first-mentioned garment, and absorbing urinary discharge from the infant in the absorbent cover where such lies against the genitalia.

3,540,450

3

2. The method of claim 1, wherein a moisture barrier is prepared by including in said first-mentioned garment a liquid impervious layer which surrounds the hole which such genitalia is projected through.

4

3. The method of claim 2, wherein such abdominal and groin regions are covered by an absorbent layer in said garment which is disposed inwardly of the liquid impervious layer and which contacts the body of the infant.
